ATTORNEY.

UNITED STATES PATENT OFFICE

WILLIAM H. BUCKINGHAM, OF BINGHAMTON, NEW YORK

CLIMBER

Application filed November 6, 1929. Serial No. 405,200.

My invention relates to climbers and particularly to climbers of that type used by linemen for the climbing of telephone, telegraph poles and the like, and has for its 5 primary object the provision of a climber so shaped and arranged to provide a maximum amount of comfort to the user and of safety.

More specifically, my invention contemplates a climber of this character, the shank 10 of which is offset adjacent the foot supporting end thereof and forwardly with respect to the foot, whereby to bring the foot rest or supporting portion of the climber forwardly of the shank and in convenient position to co- 15 operate with the instep or portion of the wearer's foot or shoe just forward of the heel, leaving the shank and spur of the climber in vertical alignment alongside the heel and leg of the wearer.

20 This positioning of the foot support of the climber by virtue of the offset in the climber shank not only renders the climber more comfortable to wear because of the better balance obtained through the use there- 25 of, but also contributes a safety factor in that by this construction the likelihood of the shank twisting or sliding relative to the wearer's leg is minimized.

Other objects and advantages in details of 30 construction and operation will be apparent as the description now proceeds, reference being had to the figures of the accompanying drawing forming a part of this application and wherein like reference numerals indicate 35 like parts.

In the drawing:—

Figure 1 is a side view of one of my improved climbers, in this instance for the left foot.

40 Figures 2 and 3 are rear views of my improved climbers, the one shown in Figure 2 being for the right foot and the one shown in Figure 3 for the left foot.

Figure 4 is a side view of my improved 45 climber for the right foot.

Figure 5 is a detail perspective view illustrating one of my improved climbers as actually used.

50 The climbers according to my invention are made in pairs, one for each foot of the

user and will be hereafter referred to in the description as a "right" or "left" climber. Figures 1 and 2 illustrate the left climber and Figures 3 and 4 illustrate a right climber. In all of the figures, the reference numeral 1 55 refers to the shank of the climber which is of desired or suitable length and adapted to extend upwardly alongside the wearer's leg and be secured to the leg adjacent the top through the medium of a suitable strap or tie device which may pass through the fixed loop 2 located adjacent the upper end of the shank. The shank 1 may be bowed slightly longitudinally as at 3 in order to bring the shank closely adjacent the wearer's leg 60 when in position thereon.

The lower end of the shank 1 is bent to form a foot support as at 4, the free end thereof extending upwardly substantially parallel with the shank 1 as at 5. This foot supporting portion 4 is adapted to be engaged by the underside of the foot at approximately the instep or just forwardly of the heel in such manner as to properly distribute the weight of the wearer when the device is used 70 for climbing. In order that this supporting portion 4 may come naturally at the instep of the foot and therefore in position to assume the balanced weight of the wearer without disturbing the position of the shank 1 75 directly alongside and parallel with the leg of the wearer, the shank 1 of each climber is adjacent its lower end offset forwardly, that is toward the front of the foot, as indicated clearly at 6 in Figures 2 and 3. This offset thus enables the shank 1 to lie directly alongside and parallel with the leg of the wearer, while the foot supporting portion 4 lies a trifle forward or at the instep position of the 80 foot of the wearer. Obviously, therefore, there will be no tendency on the part of the climber to twist or pull away from or out of alignment with the leg of the wearer when the weight of the wearer is placed on the climber, as would be the case if the shank 1 85 and the supporting portion 4 were both in the same vertical plane.

This arrangement provides a distinct improvement and advantage over the types of poles climbers heretofore commonly used and 90

wherein the foot supporting portion and the shank occupied the same vertical plane.

It will be noted also with reference to Figures 2 and 3 that the spurs or gaffs 7 are secured to the shanks 1 adjacent the lower or supporting ends thereof in central alignment longitudinally with the shanks 1, this bringing the sharpened point of each spur adjacent the lower end of the climber at the rear edge of the supporting portion 4 and in alignment with the length of the shank 1. Thus although the supporting portion 4 of the climber lies slightly forward of the center of weight, in convenient and proper supporting position, the spur lies directly in the center line of the weight to be carried centrally of the shank 1.

It will, therefore, be seen that I have provided a climber particularly useful for line-men which by its construction affords comfort to the wearer as well as safety by virtue of an offset in the shank of the climber adjacent the supporting end, enabling the climber to be attached to and fit against the foot and leg of the wearer in the most natural position, and conforming to the natural shape thereof. At the same time, the spur or gaff of the climber is positioned in alignment with the main shank of the climber and adjacent the supporting end thereof whereby when the weight of the wearer is borne by the climber such weight will be supported centrally and in longitudinal alignment with the shank, thus preventing twisting or turning of the shank 1 with respect to the leg of the wearer.

The spur or gaff 7 may be of the usual construction and suitably sharpened for biting engagement with the pole or tree to be climbed.

The outer upwardly turned end 5 of the supporting portion of the climber is provided on its outer side adjacent the free end with an eyelet 8 adapted to receive a freely swingable ring or loop 9 preferably of angular construction as shown clearly in Figure 5. One of the straight sides of the loop 9 may be provided with an anti-friction roller 10 over which is adapted to pass the fastening strap 11 by means of which the climber may be securely fastened to the foot and ankle of the wearer. This angularly formed loop 9, because of its straight sides as distinguished from a circular loop or eye, makes possible the flat engagement between the surfaces of the strap 11 and the foot of the wearer against and around which the strap lies. This is illustrated clearly in Figure 5, wherein it is clear that because of the straight side of the loop 9 around which the strap 11 engages, the flat sides of the strap engage against the foot of the wearer shown in dotted lines, thus permitting the strap to be drawn tight without discomfort to the wearer, as is the case where a loop is used of such type that the edges of the strap when secured in the man-

ner shown, engage against the foot of the wearer.

I have, therefore, provided an improved climber of the character described, the essential feature of improvement being the offset lower supporting portion of the climber with respect to the shank and spur. 70

Of course, changes may be made in details of construction and arrangement without departing from the spirit and scope of my invention. I do not limit myself, therefore, to the exact form herein shown and described other than by the appended claims. 75

I claim:—

1. A climber comprising a shank formed at one end to provide a foot support, said shank being offset forwardly to bring said support ahead of said shank, and a spur on said climber in longitudinal alignment with said shank. 80

2. A climber comprising a shank formed at one end to provide a foot support, said support being forwardly offset with respect to said shank, and a spur on said climber adjacent said foot support and in longitudinal alignment with said shank. 85

In testimony whereof, I affix my signature.

WILLIAM H. BUCKINGHAM.
